Inventor:

Ernest T. Neumann,

UNITED STATES PATENT OFFICE.

ERNST T. NEUMANN, OF CHICAGO, ILLINOIS.

LADY'S SUIT-HANGER.

No. 877,944.

Specification of Letters Patent.

Patented Feb. 4, 1908.

Application filed August 28, 1907. Serial No. 390,457.

To all whom it may concern:

Be it known that I, ERNST T. NEUMANN, a citizen of the United States, residing at Chicago, in the county of Cook and State of Illinois, have invented certain new and useful Improvements in Ladies' Suit-Hangers, of which the following is a specification.

My invention relates to that class of articles used for hanging ladies' dresses.

The object of my invention is to provide a simple and cheap hanger which will hold the full ladies' suit, a hanger in and on which the several articles can be easily and quickly adjusted and which will maintain its shape until accidentally or wilfully destroyed.

The manner in which I accomplish my object is described in the following specifications and illustrated in the accompanying drawings in which:

Figure 1 is a side elevation with parts in section to show construction. Figs. 2 and 3 are vertical cross sectional views on the line 2—2 Fig. 1, Fig. 2 showing the hanger supporting part of a dress, and Fig. 3 showing the normal position of the parts ready for use.

In the drawings A and B form the main body of the hanger. These parts are preferably of wood and are permanently joined together in any suitable manner and by any suitable means at the two points of contact C. The two parts when joined form a double arch of great strength. The top arch A is curved vertically to support a coat or jacket and the bottom inverted arch is adapted to form part of a pair of jaws adapted to hold a skirt or body part of a dress. In the center of the arch A an S hook D is permanently secured. The bend of said hook is at right angles to the length of said arch, and the lower curve E of said hook is adapted in size to admit the collar of the coat, jacket or waist hung on said arch. The end of the hook D projecting through the arch A has a loop F adapted to support a swinging wire arch I. Secured in both of the arches A and B are two tie rods G. These rods are located on either side of the center, parallel with each other. The ends H are cramped into the parts A and B and thereby permanently affixed therein. Linked in the loop F of the hook D is a swinging wire arch I. The top of this arch extends from one to the other of the tie rods G and parallel with the curve of the arch A as shown in Fig.

1. At the points J this arch is bent forward

and then down and the legs K thereby brought in front of and in vertical line with the rods G and to form a shoulder L as shown in Figs. 2 and 3. The ends M of these legs extend through an arched member N and are cramped therein and are thereby firmly secured. This member N is made shorter than the arch B so as to avoid interference with the overlapping collar or other part of the garment supported on the arch A and it forms with the part B a pair of jaws adapted to hold the top part of a dress. Encircling each of the legs K of the arch I and each of the rods G is a ring O. These rings are adapted to be hung on the shoulders L as shown in Fig. 3, and to slide down the legs K as shown in Fig. 2 and lock the jaws firmly on the garment between them.

When my invention is constructed as described and illustrated it is used as follows: The rings O are placed over the shoulders L of the arch I as shown in Figs. 1 and 3. When the rings are in this position the member N is free to be swung open from the arch B, the wire arch I pivoting on the loop F. This opening movement is limited only by the rings O when at rest on the shoulders L. The dress or skirt is then inserted between the jaws formed by the arch B and member N. The rings O are then slipped from the shoulders L down the rods G and legs K thereby securely locking the jaws on the material between them as shown in Fig. 2. The coat, jacket or waist is then placed over the arch A and the whole suit is then suspended by the hook D on a suitable support.

What I claim and desire to secure by Letters Patent is:

1. In a lady's suit hanger of the kind described, the combination consisting of two curved members affixed together in the form of a truss; an S hook secured in the center of the top cord of said truss; a pair of tie rods extending vertically through the top and bottom cords of said truss and cramped therein; a wire portion suspended from the top cord of said truss, the top of said portion being parallel with said top cord and extending from one of said tie rods to the other, the shoulders and legs of said arch extending horizontally and vertically in front of said tie rods and thereby adapted to support a member parallel with the lower cord of said truss; said member being adapted to form with the lower cord of said truss a pair of

jaws; and a pair of rings encircling said tie rods and legs of said wire portion, said rings being adapted to be hung on said shoulders and to slide down said legs and rods and to 5 thereby lock said jaws together.

2. In a suit hanger of the kind described, the combination with a main body consisting of an upper and lower member affixed together and forming a truss and means affixed 10 or attached thereto adapted to suspend it; of a pair of rods permanently affixed in the top and bottom members of said truss, said rods being spaced from and parallel with each other, and a swinging portion suspended 15 from the center of the upper member of said main body between said rods, and a member supported by said swinging portion, parallel with the lower member of said main body, and means for locking said parallel members 20 together.

3. In a suit hanger of the kind described, the combination with a main body of two parts joined together to form a truss, a pair 25 of wire rods extending from cord to cord of said truss and affixed therein, said rods being spaced from and parallel with each other, of a swinging portion suspended from the upper cord of said truss said portion extending horizontally from the center under said cord 30 to each of said rods, each end of said portion being bent to form a shoulder and to extend down in front of each rod to the lower cord, a member supported on the ends of said portion, said member being parallel with the

lower cord, and movable means for locking 35 said member and cord together.

4. In a suit hanger of the kind described, the combination with a main body forming a truss, a pair of rods extending parallel with each other from the upper to the lower cord 40 of said truss and affixed therein, a pendent member pivotally attached to the center of the upper cord of said truss, of a member corresponding in form with the lower cord of said truss, said member being supported by 45 said pendent member parallel with said lower cord, and means for locking and unlocking said member and lower cord.

5. In a suit hanger of the kind described, the combination with a main part in the form 50 of a truss, a pair of rods affixed in the cords of said truss, said rods being spaced from and parallel with each other, a pendent member loosely suspended from the central upper cord of said main part, a member affixed to said 55 pendent member and supported thereby parallel with the lower cord of said main part, of a pair of loose rings slidably supported one on each of said rods and on said pendent member adapted to be moved on said parts and to 60 lock them together.

In testimony whereof I affix my signature, in presence of two witnesses.

ERNST T. NEUMANN.
